The ornamental design for a wagering kiosk, as shown and described.

DESCRIPTION

FIG. 1 is a perspective view of the wagering kiosk;
FIG. 2 is a front view of the wagering kiosk;
FIG. 3 is a rear view of the wagering kiosk;
FIG. 4 is a top view of the wagering kiosk;
FIG. 5 is a bottom view of the wagering kiosk;
FIG. 6 is a left side view of the wagering kiosk;
FIG. 7 is a right side view of the wagering kiosk;
FIG. 8 is a perspective view of the wagering kiosk; and,
FIG. 9 is an enlarged rear view of a portion of the wagering kiosk showing the portion of the wagering kiosk in greater detail.

The broken line showing of portions of the wagering kiosk depicts environment and forms no part of the claim.
